(57) **CLAIM**

The ornamental design for an illuminator device, as shown and described.

DESCRIPTION

FIG. 1 is a left frontal elevated perspective view of the illuminator device.

FIG. 2 is a front view of the illuminator device.

FIG. 3 is a back view of the illuminator device.

FIG. 4 is a left view of the illuminator device.

FIG. 5 is a right view of the illuminator device.

FIG. 6 is a top view of the illuminator device; and,

FIG. 7 is a bottom view of the illuminator device.

The scope of this disclosure extends to the entirety of the illuminator device.

1 Claim, 7 Drawing Sheets(56)
